(57) **CLAIM**

The ornamental design for a shoe outsole, as shown and described.

DESCRIPTION

FIG. 1 is a front perspective view of a shoe outsole showing my new design;

FIG. 2 is a plan view thereof; and,

FIG. 3 is a rear perspective view thereof.

The ten unshaded regions within the shaded area, demarcated by broken lines, form no part of the claimed design. The broken lines showing the remainder of the shoe are for environmental purposes only and for no part of the claimed design.
